US00D997411S

(12) **United States Design Patent** (10) **Patent No.:** **US D997,411 S**
(45) **Date of Patent:** **** Aug. 29, 2023**

(54) **SPEAKER LAMP**

(71) Applicant: **Xin Zhong**, Ji'an (CN)

(72) Inventor: **Xin Zhong**, Ji'an (CN)

(73) Assignee: **AUDIO JAY INC.**, Beachwood, OH (US)

(**) Term: **15 Years**

(21) Appl. No.: **29/849,901**

(22) Filed: **Aug. 15, 2022**

(51) LOC (14) Cl. **26-05**

(52) U.S. Cl.

USPC **D26/51**

CLAIM

The ornamental design for a speaker lamp, as shown and described.

DESCRIPTION

FIG. 1 is a perspective view of a speaker lamp showing my new design;

FIG. 2 is a left side view thereof;

FIG. 3 is a right side view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines illustrate portions of the speaker lamp that form no part of the claimed design.

1 Claim, 7 Drawing Sheets
